UNITED STATES PATENT OFFICE.

CHARLES WHITE, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 30, 1919. Serial No. 348,324.

To all whom it may concern:

Be it known that I, CHARLES WHITE, a citizen of the United States, residing at East Orange, in the county of Essex, State of New Jersey, have invented certain new and useful Improvements in Telephone Systems, of which the following is a full, clear, concise, and exact description.

This invention relates to improvements in telephone systems and has particular reference to signaling means employed with transmission lines.

In systems of this character, it has been proposed to employ physical and phantom lines for interconnection between distant operators or subscribers. It has further been proposed to employ these lines for the transmission of signals of various natures to signal the operators at distant offices and to control the operation of repeater apparatus at intermediate offices or stations.

An object of the present invention is to provide an improved signaling circuit for use with physical and phantom lines where- 25 in the simplex physical lines are utilized, in series with the signaling circuit, for the transmission of signaling impulses designed to control means which selectively determine the particular line over which a connection 30 is to be established.

For a complete understanding of this invention, reference is made to the following description taken in connection with the accompanying drawings in which Figs. 1 to 3 35 inclusive, with Fig. 2 arranged between Figs. 1 and 3, represent a preferred embodiment of the invention; and Fig. 4 is a dia- 40 grammatic view of one of several cord circuits employed at the operators' positions.

The invention is particularly designed for use with comparatively short toll lines and is shown as comprising two distant offices X and Z and an intermediate office or station Y. Two physical lines A and C and a phantom line B are employed to interconnect the operators' positions at the distant offices. At office X there are provided two relay mechanisms, one including relays 4, 5 and 6 and the other relay 12. These mechanisms 45 are both common to the lines A, B and C and are employed for controlling the transmission of selective and disconnect signaling impulses. The first named mechanism remains operated as long as any one of the 50 lines is being used, while the relay 12 is en-

ergized only throughout the duration of a signaling impulse. Similar mechanisms are provided at office Z for the transmission of impulses to the office X. A signaling circuit passing through alternate contacts of relay 12 is simplex with the two physical lines and at office Y there is provided a means, preferably consisting of polar relays 197 and 198, the former of which is marginal, said relays being in series with the signaling 60 circuit including the physical lines extending between offices X and Y. The relays 197 and 198 are variously responsive to different potentials transmitted from office X over both physical lines to operate certain relays 70 at office Y which, in energizing, transmit the same potential to office Z. The operation of any one of the latter relays is designed to connect a battery supply to the filaments of telephone repeaters RA and RC associated 75 with the respective physical lines A and C. This battery supply remains effective as long as any one of the lines is being used. A mechanism at office Z, preferably including polar relays 207 and 208, the former being 80 marginal, is responsive to the potential transmitted from office Y to control the selection of a particular one of the lines at office Z, whereupon a signal individual to said line is operated to inform the operator that 85 a call is being extended over that line. A disconnect signal is transmitted in a similar manner from either terminating end of a line and if the other lines are idle when this signal is sent, the same will operate to restore the repeater apparatus to normal.

It is to be noted that all slow operating and releasing relays employed are conventionally illustrated as such by arrows intersecting the armatures of said relays and pointing in the direction said armatures are slow to move.

With this general description in mind, it is believed that the invention will now be fully understood from the following detailed 100 description of the operation.

Operator at office X initiates a call over line circuit A.

The operator at office X desiring to communicate with the operator at office Z, after ascertaining that line circuit A is free, inserts calling plug 13 of the selected one of the plurality of link circuits D into jack 20. The arrangement for testing the con- 105

dition of the line has been omitted from the drawings since it is unessential to a proper understanding of the invention, any well known system of this nature being suitable for use in this connection. Relays 14 and 21 operate over a circuit extending from battery through the winding of relay 14, the sleeve contacts of plug 13 and jack 20, and the winding of relay 21 to ground. Relay 22 thereupon operates over an obvious circuit and the closure of the right-hand alternate contact of relay 22 causes the operation of relay 4 over an obvious circuit whereupon relays 5 and 6 operate in succession. The closure of the middle alternate contact of relay 22 causes the operation of relays 12 and 27, relay 12 operating over a circuit extending from battery through the upper winding of relay 12, the middle normal contact of relay 26, the normal contact of relay 25, and the middle alternate contact of relay 22 to ground. Relay 27 operates over a circuit extending from battery through the winding of relay 27, the left-hand normal contact of relay 68, and the right-hand normal contact of relay 48 to the middle normal contact of relay 26 where it joins the circuit traced for relay 12. A circuit is thereupon completed from the positive terminal of the 120 volt source of current through the right-hand alternate contact of relay 27, the lower alternate contact of relay 12, the simplex conductors of line A extending from office X to office Y, the upper normal contact of relay 199, the windings of polar relays 198 and 197 in series, the lower normal contact of relay 199, the simplex conductors of line C extending from office Y to office X, the upper alternate contact of relay 12, and the middle alternate contact of relay 27 to ground. The direction of current flow and the strength of such current in this circuit is such, that relays 197 and 198 close their upper contacts whereupon relays 193 and 196 operate over a circuit established from battery through the winding of relay 193, the upper contact of relay 197, and the winding of relay 196 to ground. The opening of the normal contact of relay 193 prevents the operation of slow to operate relay 195. The closure of the right-hand alternate contact of relay 193 causes the energization of relay 189 whereupon relay 191 operates over a circuit traceable from battery through the winding and normal contact of relay 191, and the contact of relay 189 to ground. Relay 191 then locks over a circuit extending from battery through the winding and right-hand alternate contact thereof, and the normal contact of relay 190 to ground. The closure of the left-hand and middle alternate contacts of relay 191 complete the current supply circuits for the telephone repeater

equipments represented diagrammatically by the dotted rectangles RA and RC respectively, which may be of any ordinary type, the arrangement shown in Patent No. 1,413,708, issued April 25, 1922, to John Davidson, jr., being particularly adapted for use in this connection. The operation of relay 196 causes the operation of relay 181 over an obvious circuit. The closure of the left-hand and middle alternate contacts of relay 193 completes a circuit extending from the positive terminal of the 120 volt source of current through the left-hand alternate contact of relay 193, the upper alternate contact of relay 181, the simplex conductors of line A extending from office Y to office Z, the lower normal contact of relay 212, the windings of polar relays 208 and 207 in series, the upper normal contact of relay 212, the simplex conductors of line C interconnecting offices Z and Y, the lower alternate contact of relay 181, and the middle alternate contact of relay 193 to ground. The direction of current flow and the strength of current in this circuit is such that relay 207 closes its contact, and relay 208 simultaneously closes its left-hand contact. The closure of the contact of relay 207 causes the operation of relay 229 over a circuit extending from battery through the winding of relay 229, and the contact of relay 207 to ground. Lamp 223 is thereupon lighted over a circuit extending from battery through the upper right-hand alternate contact of relay 229, the right-hand normal contact of relay 222 and lamp 223 to ground. Relay 229 locks over a circuit extending from battery through the winding and left-hand alternate contact of relay 229, and the left-hand normal contact of relay 222 to ground. Although polar relay 208 also operates to close its left-hand contact, the opening of the left-hand normal contact of relay 229 occurs before relay 269 of line C can close its front contacts and thus prevents the operation of relay 269 which is slightly slow to operate. Slow to operate relay 27 in operating also causes the operation of slow to release relay 28 over a circuit extending from battery through the winding of relay 28, the left-hand alternate contact of relay 27, the right-hand normal contact of relay 26, the normal contact of relay 25, and the middle alternate contact of relay 22 to ground. The operation of relay 28 provides a temporary ground connection at its right-hand alternate contact which is extended through the right hand normal contacts of relays 48 and 68 to maintain relay 27 energized sufficiently long to permit the impulse of current to be transmitted. Relay 26 operates over a circuit extending from battery through the left-hand contact of relay 28, the left-hand normal contact and winding of relay 26, the normal

contact of relay 25, and the middle alternate contact of relay 22 to ground. Relay 26 thereupon locks over a circuit completed from battery through the alternate contact 5 and winding of relay 26, the normal contact of relay 25, and the middle alternate contact of relay 22 to ground. The operation of relay 26 opens the original energizing circuit for relay 27 and the operating circuit 10 for relay 28 and upon the release of the latter relay, the connection to ground at its right hand alternate contact is removed and relays 27 and 12 release. The release of relay 27 disconnects the 120 volt source of 15 current from the circuit including the relays 198 and 197 at office Y. Relays 181, 197, 198, 193, 196, 207 and 208 thereupon release. However, relay 191 remains operated to 20 maintain the source of current supply associated with the repeater equipments RA and RC. Relays 4, 5, 6, 14, 21, 22, and 26 at office X as well as relay 229 at office Z remain in an operated condition. Thus the 25 signaling circuit is restored to normal so that it may be employed for the transmission thereover of signaling currents for lines B and C.

Operator at office Z responds to call over line circuit A.

30 The operator at office Z observing the lighted condition of lamp 223 associated with the line A, inserts plug 13 of a suitable link circuit D thereat into jack 220 thereupon causing the operation of relays 14 and 221 over a circuit established from battery through the winding of relay 14, the sleeve contacts of plug 13 and jack 220, and the winding of relay 221 to ground. The operation 35 of relay 222 over an obvious circuit follows, thereby extinguishing the lamp 223 by the opening of the right-hand normal contact of said relay 222. The middle alternate contact of relay 222, closing before 40 the left-hand normal contact thereof opens, causes the operation of relay 226 over a circuit extending from battery through the lower right-hand alternate contact of relay 229, the right-hand normal contact and 45 winding of relay 226, the normal contact of relay 225 and the middle alternate contact of relay 222 to ground. Prior to the operation of relay 226 a circuit is established 50 for relay 227 extending from battery through the winding of relay 227, the right-hand normal contact of relay 268, left-hand normal contact of relay 248, middle normal contact of relay 226, normal contact of relay 225 and the middle alternate contact of 55 relay 222 to ground. Inasmuch as relay 227 is slow to operate, this relay will not attract its armatures before the energizing circuit therefor is opened at the middle normal contact of relay 226. Therefore, the transmission 60 of a signal from office Z to office X is, at this time, prevented. Upon the opening of the left-hand normal contact of relay 222, the locking circuit for relay 229 is opened and this relay releases. Relay 226 locks over a circuit extending from battery 65 through the alternate contact and winding of relay 226, the normal contact of relay 225 and the middle alternate contact of relay 222 to ground. Thus relay 14 of the selected link circuit D and relays 221, 222 and 226 of the line circuit A remain operated.

The closure of the left-hand alternate contact of relay 222 establishes a circuit for relay 204 which upon energizing, causes the successive operation of slow release relays 70 205 and 206. However, the energization of these relays performs no useful function at this time.

Immediately following the insertion of the plug 13 of the selected link circuit D at 75 office X into jack 20, the operator thereat actuates her listening key 15, thereby associating the usual operator's telephone set (not shown) with the link circuit in the ordinary manner. In answering the call, the 80 operator at office Z actuates the corresponding listening key 15 in the selected link circuit D at said office to similarly associate the answering operator's telephone set with the latter link circuit, whereupon the two 85 operators may communicate with each other. In the usual practice the initiating operator at office X may connect the selected link circuit D thereat, in any well-known manner, with a calling line terminating at such office 90 and the operator at office Z, in response to instructions received from the operator at office X, may similarly connect the selected link circuit D thereat with a desired called line terminating at office Z, so that the subscribers on the calling and called lines may 95 converse.

Operator at office X initiates a call over line circuit B.

100 Desiring to contemporaneously extend another connection to the office Z, the operator at office X inserts another of the plurality of link circuits D thereat into the jack 40 of line B thereby operating relay 14 of the 105 selected link circuit, and relay 41 of the line circuit B over a circuit extending from battery through the winding of relay 14, the sleeve contacts of plug 13 and jack 40, and the winding of relay 41, to ground. being transmitted for line A, the right-hand normal contact of relay 68, the middle normal contact of relay 46, the normal contact of relay 45, and the middle alternate contact of relay 42 to ground. Relay 12 operates over a circuit extending from battery through the middle winding of relay 12 to the middle normal contact of relay 46 where it joins the circuit traced for relay 47. A circuit is thereupon completed from the negative terminal of the 60 volt source of current through the right-hand alternate contact of relay 47, the upper alternate contact of relay 12, the simplex conductors of line circuit C extending from office X to office Y, the lower normal contact of relay 199, the windings of polar relays 197 and 198 in series, the upper normal contact of relay 199, the simplex conductors of the line circuit A extending from office Y to office X, the lower alternate contact of relay 12, and the middle alternate contact of relay 47 to ground. The current flows through this circuit in such a direction that relay 198 closes its lower contact. However, the amount of current flowing therethrough is insufficient to cause the operation of the marginal relay 197. Relays 194 and 196 thereupon operate over a circuit extending from battery through the normal contacts of relays 192 and 193 in series, the winding of relay 194, the lower contact of relay 198, and the winding of relay 196 to ground. As previously described, relay 196 causes the operation of relay 181 over an obvious circuit. Relay 189 also operates over an obvious circuit including the right-hand contact of relay 194. However, as previously described in detail, relay 191 is locked independently of relay 189 and consequently no effect is produced thereby. A circuit is also completed extending from the negative terminal of the 60 volt source of current through the left-hand contact of relay 194, the upper alternate contact of relay 181, the simplex conductors of line circuit A extending from office Y to office Z, the lower normal contact of relay 212, the windings of relay 207 and 208 in series, the upper normal contact of relay 212, the simplex conductors of line circuit C extending from office Z to office Y, the lower alternate contact of relay 181 and the middle contact of relay 194 to ground. The direction of current flow and the amount of current flowing in this circuit is such that relay 208 closes its right-hand contact, while marginal relay 207 remains unaffected thereby. Relay 249 operates over a circuit extending from battery through the winding of relay 249, the right-hand contact of relay 208, and the normal contact of relay 229 to ground. Relay 249 is thereupon locked over a circuit established from battery through the winding and left-hand alternate contact

of relay 249 and the left-hand normal contact of relay 242 to ground. Lamp 243 is lighted over a circuit extending from battery through the upper right alternate contact of relay 249, right-hand normal contact of relay 242, and lamp 243 to ground. 70

Relay 47 in operating as previously described also causes the operation of slow to release relay 48, over a circuit extending from battery through the winding of relay 48, the left-hand contact of relay 47, the right-hand normal contact of relay 46, the normal contact of relay 45, and the middle alternate contact of relay 42 to ground. 75 Relay 46 then operates over a circuit extending from battery through the left-hand alternate contact of relay 48, the right-hand normal contact and winding of relay 46, the normal contact of relay 45, and the middle alternate contact of relay 42 to ground. 80 Relay 46 locks over an obvious circuit. The operation of relay 46 opens the circuit for relay 48 which, after an interval, releases to open the circuits for relays 47 and 12. Relay 47 is thus released, disconnecting the 60 85 volt source of current and ground from the circuit including relays 197 and 198. Thereupon, relays 198, 194, 196, 181 and 208 release. However, relay 191 remains operated to maintain the source of current supply associated with the repeater equipments RA and RC and in addition to the relays mentioned in connection with the call over line A, relays 42, 46 and 249 remain in an operated condition. 90 The signaling circuit is 100 thereupon restored to normal. Although the closure of the right-hand alternate contact of relay 42 completes a circuit including the winding of relay 4, no effect is produced upon the system inasmuch as relays 4, 5 and 105 6 are maintained in an operated condition due to the closure of the right-hand alternate contact of relay 22.

Operator at office Z answers the call extended over line circuit B. 110

The operator at office Z, observing the lighted condition of lamp 243, inserts the plug 13 of another link circuit D thereat into jack 240 thereby causing the operation 115 of relay 14 of the selected link circuit, and relay 241 of the line circuit B, over a circuit extending from battery through the winding of relay 14, the sleeve contacts of plug 13 and jack 240 and the winding of relay 241 to ground. Relay 242 thereupon operates over an obvious circuit, the opening of the right-hand normal contact thereof extinguishing the lamp 243. The middle alternate contact of relay 242 closing before the 120 left-hand normal contact thereof opens causes the operation of relay 246 over a circuit extending from battery through the lower right-hand alternate contact of relay 249, the right hand normal contact and 125 130

winding of relay 246, the normal contact of relay 245 and the middle alternate contact of relay 242 to ground. Prior to the operation of relay 246 a circuit is completed from 5 battery through the winding of relay 247, the right-hand normal contact of relay 228, the left hand normal contact of relay 268, the middle normal contact of relay 246, the normal contact of relay 245 and the middle 10 alternate contact of relay 242 to ground. However, due to the slow operating nature of relay 247 such relay does not complete its operation before the energizing circuit therefore is disabled by the opening of the middle 15 normal contact of relay 246 so that the transmission of a signal from office Z to office Y is prevented. Relay 249 is released upon the opening of the left-hand normal contact of relay 242. In operating, relay 246 locks 20 over a circuit established from battery through the alternate contact and winding of relay 246, the normal contact of relay 245 and the middle alternate contact of relay 242 to ground. Thus relay 14 of the selected 25 line circuit D and relays 241, 242 and 246 of the phantom line circuit B remain operated. The closure of the left-hand alternate contact of relay 242 produces no material effect upon the system since relay 204 is maintained in an operated condition by means 30 of relay 222.

As in the case of the initiation of the call over line circuit A the actuation of the associated listening keys 15 enables the operators to converse over the phantom line 35 circuit B and to proceed to establish a connection between calling and called lines.

Operator at office X initiates a call over line circuit C.

40 Desiring to contemporaneously extend another connection from the office X to the office Z, the operator at office X inserts the plug 13 of another link circuit D thereat, into the jack 60 thereby operating relay 14 of the selected link circuit, and relay 61 of the line circuit C, over a circuit extending from battery through the winding of relay 14, the sleeve contacts of plug 13 and jack 60, and the winding of relay 61 to ground. 45 Relay 62 thereupon operates over an obvious circuit. The closure of the middle alternate contact of relay 62 causes the operation of relays 67 and 12, the former operating over a circuit extending from battery through the winding of relay 67, the left-hand normal contact of relay 48, the right-hand normal contact of relay 28, the middle normal contact of relay 66, the normal contact of relay 65, and the middle alternate contact of relay 62 to ground, and the latter operating over a circuit extending from battery through the lower winding of relay 12 to the middle normal contact of relay 66 55 where it joins the circuit traced for relay 67.

A circuit is thereupon completed from the positive terminal of the 60 volt source of current through the right-hand contact of relay 67, the upper alternate contact of relay 12, the simplex conductors of line circuit C, extending from office X to office Y, the lower normal contact of relay 199, the windings of relays 197 and 198 in series, the upper normal contact of relay 199, the simplex conductors of line circuit A extending from office Y to office X, the lower alternate contact of relay 12, and the middle alternate contact of relay 67, to ground. The direction of current flow through this circuit is such that relay 198 closes its upper contact but the amount of current is insufficient to cause relay 197 to close its upper contacts. Therefore, relays 195 and 196 operate over a circuit established from battery through the normal contacts of relays 192 and 193 in series, the winding of relay 195, the upper contact of relay 198, and the winding of relay 196 to ground. As before, the operation of relay 196 causes the operation of relay 181. The closure of the right-hand contact of relay 195 operates relay 189 over an obvious circuit but no material effect is produced thereby since relay 191 remains locked in an operated condition due to the call initiated over line circuit A. 95

A circuit is also completed from the positive terminal of the 60 volt source of current through the left-hand contact of relay 195, the upper alternate contact of relay 181, the simplex conductors of line circuit A extending from office Y to office Z, the lower normal contact of relay 212, the windings of relays 208 and 207 in series, the upper normal contact of relay 212, the simplex conductors of line circuit C extending from office Z to office Y, the lower alternate contact of relay 181, and the middle contact of relay 195 to ground. The direction of current flow in this circuit is such that relay 208 closes its left-hand contact, while the amount of current flowing therethrough is such that marginal relay 207 does not respond, therefore relay 269 operates over a circuit extending from battery through the winding of relay 269, the left-hand contact of relay 208 and the normal contact of relay 229 to ground. Lamp 263 is thereupon lighted over a circuit extending from battery through the upper right alternate contact of relay 269, the right-hand normal contact of relay 262 and the lamp 263 to ground. 110 115 120

125 The operation of relay 67 as previously described also causes the operation of slow to release relay 68 over a circuit extending from battery through the winding of relay 68, the left-hand contact of relay 67, the right-hand normal contact of relay 66, the normal contact of relay 65, and the middle alternate contact of relay 62 to ground. 130

When relay 68 has operated relay 66 operates over a circuit extending from battery through the left-hand alternate contact of relay 68, the left-hand normal contact and winding of relay 66, the normal contact of relay 65, and the middle alternate contact of relay 62 to ground. Relay 66 in operating locks over a circuit established from battery through the left-hand alternate contact and winding of relay 66, the normal contact of relay 65 and the middle alternate contact of relay 62 to ground. Relay 66 in operating locks over a circuit established from battery through the left-hand alternate contact and winding of relay 66, the normal contact of relay 65 and the middle alternate contact of relay 62 to ground. The operation of relay 66 causes the release of relay 68 which, after an interval, restores its armatures thereby opening at its right-hand alternate contact the circuit for relay 67. The release of relay 68 also releases relay 12. Relay 67 thereupon releases to disconnect the 60 volt source of current connected from the circuit previously traced as including relays 197 and 198 at office Y, and relays 181, 198, 195 and 208 also release. However, relay 191 remains operated to maintain closed the battery supply circuits for repeaters RA and RC and in addition to the relays mentioned in connection with the previous calls relays 62 66 and 269 remain operated. As in the previous cases the signaling circuit is restored to normal and rendered available for further use.

Although the closure of the right-hand alternate contact of relay 62 completes a circuit including the winding of relay 4 no effect is produced thereby since relays 4, 5 and 6 are maintained in an operated condition due to the closure of the corresponding contacts of relays 22 and 42.

Operator at office Z answers call extended over a line circuit C.

The operator at office Z observing the lighted condition of lamp 263 inserts a plug 13 of another selected link circuit D thereat into jack 260, thereby causing the operation of relay 14 of such link circuit, and relay 261 of line circuit C, over a circuit extending from battery, through the winding of relay 14, the sleeve contacts of plug 13 and jack 260, and the winding of relay 261 to ground. Relay 262 thereupon operates over an obvious circuit extinguishing lamp 263 and upon opening its left-hand normal contact releases relay 269. However, the middle alternate contact of relay 262, closing before the left-hand normal contact thereof opens, causes the operation of relay 266 over a circuit established from battery through the lower right-hand alternate contact of relay 269, the right-hand normal contact and winding of relay 266, the normal contact of relay 265 and the middle alternate contact of relay 262 to ground. Prior to the operation of relay 266 a circuit is completed from battery through the winding of relay 267, the right-hand normal

contact of relay 248, the left-hand normal contact of relay 228, the middle normal contact of relay 266, the normal contact of relay 265 and the middle normal contact of relay 262 to ground. However, due to the slow operating nature of relay 267 such relay does not complete its operation before the energizing circuit just traced therefor is disabled by the opening of the middle normal contact of relay 266 so that the transmission of a signal from office Z to office Y is prevented. Relay 269 is now released upon the opening of the left-hand normal contact of relay 262. In operating, relay 266 locks over a circuit completed from battery through the alternate contact and winding of relay 266, the normal contact of relay 265 and the middle alternate contact of relay 262 to ground. Thus relay 14 of the selected link circuit D at office Z and relays 261, 262 and 266 of line circuit C remain operated. The closure of the left-hand alternate contact of relay 262 produces no material effect upon the system since relays 204, 205 and 206 are maintained operated due to the closure of the similar contacts of relays 222 and 242.

As in the previous cases the actuation of the associated listening keys 15 enables the operators to converse over the line circuit C and to proceed to establish a connection between calling and called lines.

Operator of office X transmits disconnect signals to the operator at office Z.

Upon the completion of the conversation over line circuit A, the operator at office X actuates ringing key 18 in the link circuit D connected with the line circuit A, thereby operating ringing response relay 25 over a circuit extending from the source of alternating current, through the lower alternate contact of key 18, the ring contacts of plug 13 and jack 20, the lower normal contact of relay 24, one winding of the repeating coil, condenser 34 and the winding of relay 25, shunted around condenser 32, the upper normal contact of relay 24, the tip contacts of jack 20 and plug 13, and the upper alternate contact of key 18 to ground. The condenser 32 in the tip conductor of the line circuit is so proportioned relative to the condenser 34 that the shunt circuit including the latter condenser and the winding of relay 25 is resonant for the usual frequency of ringing current. Slow release relay 30 thereupon operates over an obvious circuit to short-circuit the winding of the repeating coil thereby preventing the ringing current being induced into the other section of the line circuit A through such repeating coil. The opening of the normal contact of relay 25 causes the release of relay 26. Upon the cessation of the application of the alternating current, relay 25 releases, thereupon

reestablishing the conditions existing subsequent to the insertion of plug 13 in jack 20 upon the initiation of the call so that the operations described in connection with the 5 transmission of the calling signal for line circuit A to, and including the operation of relay 229, follow as previously described. However, the operation of relay 229 causes the operation of relay 224 over a circuit extending from battery through the upper-right-hand alternate contact of relay 229, the right-hand alternate contact of relay 222 and the winding of relay 224 to ground. Relay 229 does not lock as in the previous 10 case since relay 222 is in an operated condition. The supervisory relay 16 of the link circuit D, associated with the line A at office Z operates over a circuit extending from the source of alternating current through the 15 lower alternate contact of relay 224, the ring contacts of jack 220 and plug 13, the lower normal contact of key 18, left-hand winding of relay 16, condenser 19, the upper normal contact of key 18, the tip contacts 20 of plug 13 and jack 220, and the upper alternate contact of relay 224 to ground. Supervisory lamp 17 in the link circuit associated with the line circuit A at office Z is thereupon lighted over a circuit extending from 25 battery, through the contact of relay 14, the normal contact of key 15, the lower contact and right winding of relay 16 to ground. The subsequent removal of plug 13 of link 30 circuit D at office Z from jack 220 and of plug 13 of link circuit D at office X from jack 20 restores all apparatus at offices X and Z of line circuit A to normal.

Upon the completion of the conversation over the phantom line circuit B, the operator at office X actuates ringing key 18 of the link circuit D connected with the line circuit B at office X, thereby operating relay 45 over a circuit similar to that traced for relay 25 and causing the subsequent operation of relay 50 in a manner similar to that described for relay 30 and also releasing relay 46. Upon the release of the ringing key an impulse is transmitted to the office Z to cause the operation of relay 249 in a 50 manner similar to that described in connection with the initiation of the call over the line circuit B. However, as described in connection with the transmitting of the disconnect signal over the line circuit A, relay 244 is operated over a circuit extending from battery, through the upper right-hand alternate contact of relay 249, the right-hand alternate contact of relay 242, and the winding of relay 244 to ground. Relay 16 in the 55 link circuit D associated with the line circuit B at office Z is thereupon operated to light the associated supervisory lamp 17 to give a disconnect signal to the operator at office Z in the manner described in connection with the line circuit A. The subse-

quent removal of the link circuit D from association with line circuit B restores to normal all apparatus for such line circuits at offices X and Z.

In a similar manner, the actuation of the ringing key 18 in the link circuit D associated with the line circuit C at office X upon the completion of the conversation over such line causes the operation of relays 65 and 70 and the release of relay 66. The release of the ringing key transmits an impulse to the office Z for operating relay 269 as in the case of the initiation of the call over such line circuit. As described in connection with the disconnect signal for the other line circuits, however, relay 264 is operated over a circuit extending from battery through the upper right-hand alternate contact of relay 269, the right-hand alternate contact of relay 262 and the winding of relay 264 to ground. As before, the supervisory relay in the associated link circuit at office Z is operated to cause the lighting of the associated supervisory lamp to give a disconnect signal to the operator at office Z. In this case, the removal of the plugs 13 of the associated link circuits D from the jacks 60 and 260 of line circuit C causes the restoration to normal of all apparatus individual to the line circuit C at the offices X and Z.

In sending the disconnected signal from office Z, relays 225 and 230 of line A, relays 245 and 250 of line B and relays 265 and 270 of line C are controlled in the same manner as described in connection with relays 25 and 30 when the disconnect signal for line A is transmitted from office X. Also, relays 186, 187, and 188 are controlled in a manner similar to that of relays 196, 197 and 198 when signals are transmitted from office Z.

The repeater equipments are rendered ineffective.

Although the release of relays 22 and 42 accompanying the removal of the plugs 13 from jacks 20 and 40 introduces a break in the circuit of relay 4, such relay is not released until the plug is removed from the last of the engaged jacks which releases relay 62. Upon the release of relay 4, slow release relays 5 and 6 release successively. However, during the interval between the release of relay 4 and the subsequent release of relay 6, a circuit is completed from battery, through the lower winding of relay 12, the left-hand alternate contact of relay 6, and the left-hand normal contact of relay 4 to ground. Relay 12 thereupon operates to complete for this period a circuit extending from the negative terminal of the 120 volt source of current through the right-hand alternate contact of relay 6, the right-hand normal contact of relay 4, the lower

alternate contact of relay 12, the simplex conductors of line circuit A extending from office X to office Y, the upper normal contact of relay 199, the windings of relays 198 and 197 in series, the lower normal contact of relay 199, the simplex conductors of line circuit C extending from office Y to office X, the upper alternate contact of relay 12, the middle normal contact of relay 4, and the middle alternate contact of relay 6 to ground. The direction of current-flow and the amount of current flowing through this circuit is such that relay 197 and 198 close their lower contacts. The closure of the lower contact by relay 197, causes the operation of relays 192 and 196 over a circuit extending from battery, through the winding of relay 192, the lower contact of relay 197, and the winding of relay 196 to ground. The closure of the alternate contact of relay 192 operates relay 190 over an obvious circuit and the opening of the contact of the latter relay releases relay 191 so that the filament current-supply circuits of repeaters RA and RC are opened. The opening of the normal contact of relay 192 removes the battery connection from one terminal of the winding of slow to operate relay 194 so that such relay does not operate. As in the previous cases, relay 196 in operating causes the operation of relay 181 but no material effect is produced thereby.

Although in each case the transmission of the signals has been described as being initiated at office X and received at office Z it is evident that since the equipments at the two offices are duplicates, such signals may be transmitted from office Z to office X with equal facility. Also due to the arrangement of the apparatus at office Y it is apparent that the repeaters can be controlled from either office X or Z and the signals repeated in either direction. Although the system has been described as including the intermediate office or station Y at which the repeating equipments are placed and provision is made for repeating the signals received from either of the widely separated offices or stations X and Z it may be possible to omit such intermediate stations on comparatively short line units. Likewise in connection with extremely long lines it may be necessary to introduce several intermediate repeater stations of the type shown in Fig. 2.

From the above description it will be apparent that four conductors interconnecting two widely separated offices may be employed for three line circuits all of the selective signaling being transmitted over the phantom circuit. It will also be obvious that the filament current-supply circuits of the repeater sets are closed when any one of the line circuits is selected for use and are

maintained in an operative condition as long as any one of the lines is in use. 65

What is claimed is:

1. In a telephone system, two distant offices, operators' positions thereat, physical and phantom lines connecting said offices, a 70 signaling circuit including conductors connected to certain of said lines, means for transmitting a signalling impulse for any one of said lines over said signaling circuit, means at one office common to said physical 75 and phantom lines and operated only when a signalling impulse for any one of them is transmitted, and means at the other office responsive to the operation of the last-named means for selectively indicating to the operator at said other office the line over which a call has been initiated. 80

2. In a telephone system, two distant offices, physical and phantom lines connecting said offices, a signaling circuit connected to certain of said lines, means for transmitting a signalling impulse for any one of said lines over said signaling circuit and the lines to which said circuit is connected in series, means at one office common to said physical 90 and phantom lines and operated only when a signalling impulse for any one of them is transmitted, and means at the other office responsive to the operation of the last-named means for selectively indicating at said other 95 office the line over which a call has been initiated.

3. In a telephone system, two distant offices, physical and phantom lines connecting said offices, a signaling circuit connected to 100 said physical lines, means responsive to the initiation of a call on any one of said lines for transmitting a signalling impulse over said signaling circuit and said physical lines in series, means at one office common to said 105 lines and operable when a call is initiated for rendering said signaling circuit effective, and means at the other office responsive to the operation of the last-named means for selectively indicating at said other office the 110 line over which a call has been initiated.

4. In a telephone system, two distant offices, a plurality of transmission lines connecting said offices, a signaling circuit connected to certain of said lines, means for 115 transmitting a signalling impulse for any one of said lines over said signaling circuit, a relay at one office common to said lines and operated only when a signalling impulse for any one of them is transmitted, and polar 120 relays at the other office responsive to the operation of the first-named relay for selectively indicating at said other office the line over which a call has been initiated.

5. In a telephone system, two distant offices, an intermediate office, a plurality of transmission lines interconnecting said offices, a signaling circuit connected to certain

of said lines, means for transmitting a signaling impulse for any one of said lines over said signaling circuit and the lines to which said circuit is connected, means at one of said 5 distant offices common to said lines and operated only when a signaling impulse for any one of them is transmitted, polar relays at said intermediate office in series with said signaling circuit and the lines to which said 10 circuit is connected, said polar relays being responsive to a signaling impulse transmitted over said signaling circuit, and polar relays at the other distant office responsive to the operation of the first-named polar relays 15 for selectively determining the line at said other office over which a call has been initiated.

6. In a telephone system two distant offices, an intermediate office, a plurality of 20 transmission lines interconnecting said offices, a signaling circuit connected to certain of said lines, means for transmitting a signaling impulse for any one of said lines over said signaling circuit and the lines to which 25 said circuit is connected, means at one of said distant offices common to said lines and operated only when a signaling impulse for any one of them is transmitted, polar relays at said intermediate office in series with said 30 signaling circuit and the lines to which said circuit is connected, said polar relays being responsive to a signaling impulse transmitted over said signaling circuit, repeater apparatus associated with certain of said

lines, means responsive to the operation of 35 said polar relays for rendering said repeater apparatus effective, and other polar relays at the other distant office responsive to the operation of the first-named polar relays for 40 selectively determining the line at said other office over which a call has been initiated.

7. In a telephone system, two distant offices, operators' positions thereat, a plurality of transmission lines connecting said offices, a signaling circuit including conductors connected to certain of said lines, means for transmitting a signaling impulse for any one of said lines over said signaling circuit, means at one office common to said lines and operated only when a signaling impulse for 50 any one of them is transmitted, means at the other office responsive to the operation of the last-named means for selectively indicating to the operator at said other office the line over which a call has been initiated, 55 other means at the first named office also common to said lines and operated when a call is initiated on any one of them, said other means remaining operated while any one of the lines is in use, and means for releasing said other means to transmit a disconnect impulse over said signaling circuit and certain of said lines in series.

In witness whereof, I hereunto subscribe my name this 26th day of December, A. D. 65 1919.

CHARLES WHITE.
